UNITED STATES PATENT OFFICE.

ROBERT EHRLICH, OF BALTIMORE, MARYLAND.

GREASE-CUP.

1,110,120.

Specification of Letters Patent. Patented Sept. 8, 1914.

Application filed January 26, 1914. Serial No. 814,456.

To all whom it may concern:

Be it known that I, ROBERT EHRLICH, a citizen of the United States, residing at Baltimore, Maryland, have invented certain new and useful Improvements in Grease-Cups, of which the following is a specification.

It is the object of my invention to provide a grease-cup which is economical in dispensing the grease to the parts to be lubricated, especially to the bearings, etc. of automobiles, flying machines, agricultural machines and other machines frequently subjected to hard shocks.

15 A further object of the invention is to provide a grease-cup avoiding the accidental loss of the lubricant.

20 A still further object of the invention consists in the arrangement of retarding means arranged to yieldingly resist the rotary movement of the cover on the cup to prevent the top or cover of the grease-cup from accidentally working loose and coming off the cup while in use and to centralize the pin 25 secured to the cup-cover or top for most economically, however yet effectively dispensing the lubricant.

With this end in view the cap or cover has secured thereto an inwardly extending three-faced pin adapted to be engaged by the ends of a peculiarly bent spring located within the shank of the cup for yieldingly resisting the rotary movement of the cover on the cup by engaging at a time two of the 35 faces of the pin.

The spring is exchangeably located in the upper part of the shank of said cup so that a broken or injured spring may easily and conveniently be exchanged for a new one.

40 Other objects of my invention will become apparent from the description and the accompanying drawing forming part of this specification, in which:

Figure 1 is a bottom plan view of the cap 45 or cover illustrating the manner in which the three-edged pin is firmly secured thereto. Fig. 2 is a vertical sectional view of a grease-cup with my invention applied thereto. Fig. 3 is a top plan view of the grease cup 50 proper showing the position of the spring therein in engagement with two faces of the pin. Fig. 4 is a front elevation of the grease-cup.

Similar letters of reference indicate corresponding parts in the figures.

Referring to the drawing, 10 represents the

member which is called the cup. This member has an externally threaded upper flange 11 provided with an inner shoulder 12 for the support of a strong leaf-spring 13 resting with its lower edge upon said shoulder and tightly engaging with its outer face the inner wall of the circular bore 14 of said cup above said shoulder. The ends of the spring are peculiarly bent and extend inwardly at an angle 15 to each other with their upper free ends 16 forming the apex of said angle located vertically above the bore 25, and in tight engagement with each other.

Below the flange 11 the outer face of the cup-body is nut-shaped as at 17 for the engagement of a suitable tool, and a shank 18 with exterior threads is integrally made with said body and adapted to be suitably secured to the part of a machine to be lubricated.

The cap or top 19 of the grease-cup 10 is provided with an outer corrugated flange 20 near its upper end and an inner threaded wall 21 adapted to engage the outer thread of the upper flange 11 of the cup 10. A three-cornered pin 22 is firmly embedded in the metal of the cover 23 of the top at the inner side thereof and its point of connection with said top is strengthened by a suitably shaped strengthening plate 24 or the like.

It will be clear that when screwing the top 19 to the cup 10 the pointed three-edged pin will in the manner of a wedge engage 90 two of the faces of the inner free ends of the spring 13 and try to pry the same asunder so that these ends are frictionally engaging two of the faces of said pin and offer a suitable resistance to the parts preventing the 95 top from accidentally working loose and coming off the cup while in use. This results also in preventing the accidental loss of any part of the lubricant and makes the device to a highly economical one.

100 The device operates as follows: The lubricating grease is forcibly pressed into the top or cap until the same is completely filled therewith, whereafter the cap is secured to the cup which will result in pressing the 105 grease through the lower opening 25 onto a bearing or other part to be greased.

It is to be understood that changes may be made in the size and shape of the single parts and general arrangement of my 110 grease-cup without deviating from the spirit and scope of the present invention.

However what I claim is:

1. A grease-cup of the character described comprising an interiorly threaded cylindrical cap provided with a corrugated flange near its upper end, and an exteriorly threaded cup, adapted to be screwed one onto the other, a three-cornered pin firmly secured to the inner top wall of said cap, means for strengthening this connection, a shoulder within the bore of said exteriorly threaded cup, a spring resting with its lower edge upon said shoulder and with its outer face against the inner wall of said bore and having its free ends extending inwardly at an angle to each other, bent in tight engagement at the apex of the angle and adapted to be pried asunder by the introduction of the wedge shaped pin between said ends during the screwing of said cap onto said cup, for frictionally engaging two sides of said pin and to yieldingly resist the rotary movement of the cap on the cup.
2. A grease-cup of the character described comprising an interiorly threaded cylindrical cap provided with a corrugated flange near its outer upper end, and an exteriorly threaded cup adapted to be secured one onto the other, a three-cornered pin firmly secured

to the inner top wall of said cap, a strengthening plate for strengthening this connection, a shoulder within the bore of said exteriorly threaded cup, a nut-shaped part and a threaded flange integrally made with said cup and both provided with a bore communicating with the bore of the cup, a spring resting with its lower edge upon said shoulder and with its outer face against the inner walls of said bore in the upper part of said cup, and having its ends extending inwardly at an angle to each other, with the apex of said angle vertically above the bore of said nut-shaped part and lower flange formed by the tightly engaging separated ends of said spring, adapted to be pried asunder by the introduction of the pointed wedge-like operating pin between said ends during the screwing of said cap onto said cup, for frictionally engaging two sides of said pin and to yieldingly resist the rotary movement of the cap on the cup.

In testimony whereof I affix my signature in presence of two witnesses.

ROBERT EHRLICH.
